UNITED STATES PATENT OFFICE.

WILLIAM JAMES WALKER, OF FRANKLIN, MASSACHUSETTS.

IMPLEMENT FOR SMOOTHING OR POLISHING METALLIC SURFACES.

SPECIFICATION forming part of Letters Patent No. 296,370, dated April 8, 1884.

Application filed January 18, 1884. (No model.)

To all whom it may concern:

Be it known that I, WILLIAM JAMES WALKER, of Franklin, in the county of Norfolk, of the Commonwealth of Massachusetts, have invented a new and useful Improvement in Implements for Smoothing or Polishing Metallic Surfaces; and I do hereby declare the same to be described in the following specification and represented in the accompanying drawings, 10 of which—

Figure 1 is a side elevation, and Figs. 2 and 3 transverse sections in planes at right angles to each other, of an implement embodying my invention, the nature of which is defined in 15 the claims hereinafter presented.

This implement, as shown in the drawings, is designed for smoothing the curved and plane surfaces of hat-dies. Its smoothing-head A is composed of an elastic hollow vessel, *a*, of 20 proper shape, of vulcanized india-rubber, and a charge, *b*, of liquid—as water, for instance, though in some cases an oil of suitable kind may be substituted.

On the outer surface of the vessel *a* there is 25 to be a covering, *l*, of a suitable abrasive or polishing material. The said vessel has a metallic neck or carrier, *B*, properly constructed not only to hold it firmly, with a water-tight joint between them, and to admit of 30 the charge of water being passed or forced through it into the vessel, but also for attaching or securing it (the said neck) to a mandrel or shaft or other device for rapidly revolving the implement. To this end the neck *B* is composed in part of a tubular shank, *c*, and a disk-shaped flange, *d*, extending therefrom concentrically at its lower end. This shank *c* is 35 screw-threaded on its periphery to receive or screw into a tubular nut, *e*, between which and the flange *d* there is a disk, *f*, of metal, through 40 which the screw *c* passes centrally. On the upper end of the shank *c* is an elastic and water-tight packing, *g*, which is forced down upon said end by a screw, *h*, screwed into the nut *e*, the latter projecting, as shown, above the 45 screw *h*. Furthermore, a tapering cock, *i*, extends through the nut *e* and the shank *c*. Besides serving to keep the nut from revolving on the shank, this cock is either to open or 50 close communication through the bore of the said shank. The head *i* of this cock, like that

of a common screw, is nicked to receive the blade of a screw-driver when used for revolving the cock. The upper part of the head *A* extends, as shown, between the flange *d* and 55 the disk *f*, and, being of a water-proof and elastic material, will form with the flange and disk, when the latter is forced down closely by the nut *e*, a water-proof joint between the said head *A* and the metallic neck *B*. 6c

Preparatory to charging the head with water or other proper liquid practically incompressible, the cock is to be turned open, to allow the charge to be passed or forced into the head, which having been accomplished 65 the cock is to be closed, the packing *g* put in place, and the screw *h* screwed down hard upon it. The packing and screw are additional means of preventing leakage of the charge, and, besides, serve to cover the upper open 70 end of the shank *c*, in order to prevent dirt or emery or the grinding or polishing material used on the outer surface of the head *A* from getting into the bore of the shank *c* and stopping such or wearing the cock. 75

I make no claim to a shoe-sole buffer made as represented in either of the United States Patents Nos. 190,174 and 227,839, such being somewhat analogous to my smoothing or polishing implement, as hereinbefore described, 80 but differing therefrom in important particulars, especially in having no elastic and water-proof head or its inelastic charge of water or liquid. Furthermore, there is in neither of the said shoe-sole buffers, as in my smoothing 85 implement, a nut extended upward beyond its male screw, and having within it the said nut, a packing, and a screw beyond which the nut is projected upward.

The elastic and water-proof head of vulcanized india-rubber and its charge of water or other like inelastic liquid is found when in use, and covered on its external surface with emery or other suitable abrasive or polishing material, to be capable of operating to better 90 advantage than a head of felt, or one made of an inelastic bag or covering of leather or cloth, and a stuffing therefor of hair, wool, or other like material.

By reason of the elasticity and water-proof 100 character of the part *a* of the head and the inelasticity of the charge *b* of liquid thereof, the

head, when revolving against a surface, will adapt itself to the corners and serrations thereof, and substantially maintain its normal form to far better advantage, and with new and useful effects, comparatively speaking.

I claim—

1. The combination of the tubular and flanged screw *c* and the disk *f* with the nut *e*, screwed upon and extended beyond the said screw, all being substantially as represented.
2. The combination of the tubular and flanged screw *c* and the disk *f* with the nut *e*, screwed on and extended beyond the screw, as set forth, and with the screw *h* and packing

g arranged in the said nut, and with respect to the said screw *c*, all being substantially as represented.

3. The combination of the screw-threaded tubular shank *c*, having the disk-shaped flange *d*, screw-threaded nut *e*, and disk *f*, as described, with the cock *C*, extended into the nut *e* and tubular screw *c*, and with the waterproof and elastic vessel *a*, applied to such neck, all being substantially as represented.

WILLIAM JAMES WALKER.
